(57) **CLAIM**

The ornamental design for a makeup tool, as shown and described.

DESCRIPTION

FIG. 1 is a front perspective view of an almond shaped left side attachment for a makeup tool kit in accordance with the

present design, the almond shaped right side attachment being a mirror image of the almond shaped left side attachment thereof;

FIG. 2 is a front elevational view thereof, the almond shaped right side attachment being a mirror image of the almond shaped left side attachment thereof;

FIG. 3 is a rear elevational view thereof, the almond shaped right side attachment being a mirror image of the almond shaped left side attachment thereof;

FIG. 4 is a left side elevational view thereof, the almond shaped right side attachment being a mirror image of the almond shaped left side attachment thereof;

FIG. 5 is a right side elevational view thereof, the almond shaped right side attachment being a mirror image of the almond shaped left side attachment thereof;

FIG. 6 is a top plan view thereof, the almond shaped right side attachment being a mirror image of the almond shaped left side attachment thereof;

FIG. 7 is a bottom plan view thereof, the almond shaped right side attachment being a mirror image of the almond shaped left side attachment thereof;

FIG. 8 is a front perspective view of the almond shaped left side attachment for a makeup tool kit in a curved configuration in its environment thereof, the almond shaped right side attachment being a mirror image of the almond shaped left side attachment thereof;

FIG. 9 is a front perspective view of a round shaped left side attachment for a makeup tool kit in accordance with the present design, the round shaped right side attachment being a mirror image of the round shaped left side attachment thereof;

FIG. 10 is a front elevational view thereof, the round shaped right side attachment being a mirror image of the round shaped left side attachment thereof;

FIG. 11 is a rear elevational view thereof, the round shaped right side attachment being a mirror image of the round shaped left side attachment thereof;

FIG. 12 is a left side elevational view thereof, the round shaped right side attachment being a mirror image of the round shaped left side attachment thereof;

FIG. 13 is a right side elevational view thereof, the round shaped right side attachment being a mirror image of the round shaped left side attachment thereof;

(Continued)

FIG. 14 is a top plan view thereof, the round shaped right side attachment being a mirror image of the round shaped left side attachment thereof;

FIG. 15 is a bottom plan view thereof, the round shaped right side attachment being a mirror image of the round shaped left side attachment thereof; and,

FIG. 16 is a front perspective view of the round shaped left side attachment for a makeup tool kit in a curved configuration in its environment thereof, the round shaped right side attachment being a mirror image of the round shaped left side attachment thereof.

The broken lines of the makeup tool or portion thereof shown in the drawing illustrate portions of the makeup tool that form no part of the claimed design.

1 Claim, 10 Drawing Sheets
